UNITED STATES PATENT OFFICE

FRANK J. FRANSON, OF TOWER, MINNESOTA

PORTABLE TOURIST SINK

Application filed July 16, 1926. Serial No. 122,908.

My invention relates to portable tourist sinks, wherein it is desired to provide a sink which may be adaptable for use out in the open, such as in tourist camps where the sink may be practically self contained as to the compartments for washing dishes and the like, together with heating means forming a complete unit, all of which is portable so as to be readily moved or most conveniently 10 placed.

A feature of the invention resides in means for providing a sink with burners beneath the sink compartments and a closure in front of the burners so that the heat from the burners will not interfere with the person using 15 the sink and permitting water held in the sink to be readily heated as may be desired.

My sink is of a nature to provide a unit including several compartments which may 20 be of a desired depth so that a fairly good amount of water can be contained within the same and if necessary the compartments or one of them can be used as a boiler compartment in conjunction with the burner to boil 25 the water or articles within the same. The unit structure of the sink with the several compartments for the water and burners for each compartment, together with a supply tank for liquid fuel such as coal oil, or gaso- 30 lene or other liquid fuel provides a unique structure for a sink particularly adapted for tourist camps and purposes of that nature.

It is also a feature of the invention to provide drain boards on either side of the 35 sink which may be pivotally attached to the body of the sink in a manner so that the drain board can be folded over across the top of the sink to close the same when it is not in use or so that one of the compartments may be closed if desired while the other is in use. In a tourist sink for out of doors this would 40 be of advantage because when the sink is not in use it can be readily closed, keeping dirt out of the sink compartments.

These features, together with other details 45 and objects of my invention, will be more fully and clearly set forth in the specification and claims.

In the drawings forming part of the specification:

Figure 1 is a perspective view of my sink as it would appear in use.

Figure 2 is a front elevation of the same showing some of the parts in dotted position.

My sink A is designed of a construction to provide a substantial body 10 and is formed of any suitable material to form the compartments 11 and 12. These compartments have a fairly deep nature so as to provide a 60 depth for the water of the sink and to permit the washing of dishes or clothes in the sink if it is desired.

The compartments 11 and 12 are supported by the frame of the sink A and are portably held elevated by the legs 13, so as to hold the compartments at the desired height from the ground and to form means for rigidly and substantially supporting the body of the sink. In construction these legs can be of 65 angle iron and can either be attached rigidly to the body 10 or be made so as to be disengageable from the body so that the sink can be knocked down for shipment or storage into a compact set.

The leg members 13 are adapted to support the under plate member 14 which extends along beneath the compartments 11 and 12. Burners B of any suitable nature are secured 70 to the plate member 14 and project upwardly so that the upper edge 15 of these burners will come in close proximity to the underside 75 of the compartments of the sink A to permit the heating of the water within the compartments.

The burners B are adapted to be supplied with fuel through the pipe 17 which connects with the supply tank 18. The tank 18 is formed with an outer casing 19 and a cover 20 which is hingedly secured to the casing 80 so that the cover may be tipped to one side as illustrated in dotted outline, Figure 2.

Within the casing 19 I desire to provide a tank 21 for the liquid fuel which may be 85 of a nature so that this tank can be lifted out to fill the same or drain the contents of the tank if it is desired. By this means of construction for the supply tank 18 and the connection with the burners B I provide 90 a suitable means for heating the water within 95 100

the compartments 11 or 12 of the sink A, which is quite desirable and adaptable to a portable tourist sink, more particularly for the reason that the tourist can fill the tank 5 21 with liquid fuel when they are ready to use the sink and if all of the fuel is not used up from the tank they can empty the same before they leave the tourist camp.

The unit construction of the sink A with- 10 the burners attached and the portable nature of the entire unit permit the sink to be used at any convenient place or moved readily, a feature which is quite important for an article of this nature in a tourist camp.

15 It also is readily apparent that this construction of sink can be used in other places where it is desirable to have a unit sink and heating means so that the water can be heated and the operation of washing dishes or 20 other articles may be more easily accom- plished.

The sink A is provided with a suitable drain valve 24 which permits the sink to be drained out through the pipe 25 after it has been used.

25 The drain pipe 25 of the sink may be connected to the ordinary sewerage drain if it is desired when my sink is used in a building where sewerage is ordinarily connected.

To guard the user of my sink A against 30 the heat of the burners B I provide closures 26, which are in the form of doors adapted to close the front of the lower portion of the sink A so that the heat from the burners will not be directed up to the body of the 35 person using the sink. The closure doors such as 26 can be provided for the front and back of the sink if it is desirable so that the sink can be used from either side.

The sink A is provided with drain boards 28 40 and I have found it desirable to hingedly connect the drain boards 28 at 29 to the body of the sink A so that the drain boards 28 can be folded over across the top of the compartments 11 and 12 as is illustrated of one 45 of the drain boards 28 in dotted outline, Figure 2. When the sink A is not in use it is desirable to close the top of the same to keep the dirt out of the compartments 11 and 12, especially when the sink is used as a tourist's 50 outdoor sink and this construction also permits the sink to be folded into a more compact set so that in shipping or in otherwise storing the sink A, it can be taken apart and folded together to provide a comparatively 55 small size.

In accordance with the patent statutes I have described the principles of operation of my invention and have illustrated a particular construction in the drawings. I desire to 60 have it understood that these illustrations are only suggestive of a means of carrying out my invention and that the same can be applied to other uses and made in other forms within the scope of the following claim:

65 I claim:

A portable sink including, a body portion having deep sink compartments, heating means for each of the compartments to heat the water within the same, and drain board cover members hinged to the walls of said compartments and having wide portions adjacent the hinges for supporting the drain boards when open for closing said compartments and providing a drain when open.
